[57] CLAIM

The ornamental design for a wide format ink jet printer with multiple media input trays, as shown.

DESCRIPTION

FIG. 1 is a perspective view of a wide format ink jet printer with multiple media input trays showing a new design. One of the media input trays is shown in a position to accommodate media of a larger size.

FIG. 2 is a left side elevation view of the ink jet printer in FIG. 1.

FIG. 3 is a right side elevation view of the ink jet printer in FIG. 1.

FIG. 4 is a front elevation view of the ink jet printer in FIG. 1.

FIG. 5 is a back elevation view of the ink jet printer in FIG. 1.

FIG. 6 is a top plan view of the ink jet printer in FIG. 1; and, FIG. 7 is a bottom plan view of the ink jet printer in FIG. 1.
